CLAIM

The ornamental design for a pacifier, as shown and described.

DESCRIPTION

FIG. 1 is an upper right front perspective view of a pacifier of my new design;

FIG. 2 is a front elevational view of the design of FIG. 1;

FIG. 3 is a rear elevational view thereof;

FIG. 4 is a top plan view, the bottom plan view being identical thereto; and,

FIG. 5 is a left side view thereof, the right side view being the mirror image thereof.
